UNITED STATES PATENT OFFICE.

OLIVER J. MOUSSETTE, OF BROOKLYN, NEW YORK.

GRINDING-MILL.

No. 825,148.

Specification of Letters Patent.

Patented July 3, 1906.

Application filed December 28, 1904. Serial No. 238,631.

To all whom it may concern:

Be it known that I, OLIVER J. MOUSSETTE, a citizen of the United States, residing at Brooklyn, in the county of Kings and State 5 of New York, have invented new and useful Improvements in Grinding-Mills, of which the following is a specification.

This invention consists in the features of construction set forth in the following specification and claims, and illustrated in the annexed drawings, in which—

Figure 1 is a side elevation of a grinding-mill embodying this invention. Fig. 2 is a view like Fig. 1 in section. Fig. 3 is an end 15 view of Fig. 1. Fig. 4 is an edge view of a section of the mill.

In the drawings is shown a case composed of sections *a*. This case is supported on wheels *b* of shafts *c*. A suitable pulley or 20 driving means rotates the wheels or some of them so as to cause the case or shell *a* to roll or rotate. This motion is easy and requires small expenditure of force. In this rotary case is a crusher or weight. This crusher is 25 composed of sections *d*, connected together by suitable means to allow a certain looseness or play to the sections with respect to one another, but compelling the crusher-sections to roll or turn together. This crusher 30 is loose in and of less diameter than the case so as to roll upon the inner surface thereof. These crusher-sections are shown hollow or tubular, and each section has a web *e* therein. A link-bolt *f* being connected or secured to 35 each web and these links engaging one another these sections are united or made to move in unison.

The adjacent faces or the part of each crusher-section which faces the other is 40 shown roughened or corrugated. The outline or taper of the crusher or weight *d* is different from that of the case. Such non-conformance, as seen in Fig. 2, causes the adjacent crusher-faces to gape or be out of parallel. The rolling of the crusher causing 45 these faces to move parts to and from one another material entrapped between the sections or caught or seized by the corrugations or teeth will be comminuted or crushed or 50 carried about.

The case is shown tapered from its center portion in each direction in the axis of rotation. The crusher is likewise tapered, but in 55 different degree. The case has an entrance and exit at *g* and *h*, respectively. These

openings or mouths allow continuous flow or passage of water or fluid during operation or while the case is rotating. The tubular form of the crusher-sections also allows flow through the apparatus. 60

A cover *i* is shown for a withdrawing-opening. This cover can be held removably in place by suitable means. A cross-piece or rod *k*, engaging lugs or eyes *m* on the case and provided with a screw, can hold the 65 cover in place in the opening of the case.

The meeting rims of the case-sections are shown as flanges with groove-sections for a packing *n*, such as a piece or ring of rubber or other suitable material. The flanges being 70 bolted directly together or metal coming to metal the bolting can be firmly made. At the same time the packing prevents leakage.

By having the inlet *g* higher or smaller than outlet *h* no backflow can occur, but wa- 75 ter entering at *g* will pass off at *h*.

As the case is supported at four points by the four rotary wheels *b*, said case needs no other supports or gudgeons to maintain the same in place. 80

What I claim as my invention, and desire to secure by Letters Patent, is—

1. A grinding-mill comprising a rotary case tapering from the center toward each end, and a crusher arranged within the case 85 and composed of flexibly-connected sections of a conicity different from that of the case and adapted to grind or comminute material between their adjacent faces, each of said crusher-sections tapering from the inner to- 90 toward the outer end thereof and conforming in contour to the shape of the casing so as to nest therein and prevent displacement of the crusher during rotation of the casing, the taper of the crusher being of somewhat differ- 95 ent degree to the taper of the case so as to cause the meeting edges of the crusher-sections to gape or stand at an angle to one another.

2. A grinding-mill comprising a rotary 100 case tapering from the center toward each end, and a crusher arranged within the case and composed of sections of a conicity different from that of the case linked together and adapted to grind or comminute material be- 105 tween their adjacent faces, each of said crusher-sections tapering from the inner to- toward the outer end thereof and conforming in contour to the shape of the casing so as to nest therein and prevent displacement of the 110

crusher during rotation of the casing, the taper of the crusher being of somewhat different degree to the taper of the case so as to cause the meeting edges of the crusher-sections to gape or stand at an angle to one another.

3. In a grinding-mill a rotary case and tubular or open crusher-sections each having a web in its interior clear of the edges, and link-bolts respectively secured to the webs and connected to one another.

4. In a grinding-mill, a tapered rotary case and crusher-sections of different taper than the case and having their opposing end faces corrugated.

5. In a grinding-mill a rotary case tapering from the center toward each end and having openings along the axis of rotation and crusher-sections of tubular shape placed end to end and extended in like direction so

as to allow flow during the operation through the crusher and both ends of the case.

6. In a grinding-mill a rotary case tapered from its center portion in each direction in the axis of rotation, tubular or hollow crusher-sections of different taper from the case, and a connection between the sections, said case having openings for the passage of fluid during operation and a withdrawing-opening with cover therefor, said crusher-sections being placed end to end and being detached from the case so as to roll freely therein.

In testimony whereof I have hereunto set my hand in the presence of two subscribing witnesses.

OLIVER J. MOUSSETTE.
